US00D934279S

(12) **United States Design Patent** (10) Patent No.: **US D934,279 S**
Kögler (45) Date of Patent: **** Oct. 26, 2021**

(54) **DISPLAY SCREEN OR PORTION THEREOF WITH GRAPHICAL USER INTERFACE**(71) Applicant: **VOLKSWAGEN AKTIENGESELLSCHAFT**,
Wolfsburg (DE)(72) Inventor: **Indra-Lena Kögler**, Wolfsburg (DE)(73) Assignee: **VOLKSWAGEN AKTIENGESELLSCHAFT**,
Wolfsburg (DE)(***) Term: **15 Years**(21) Appl. No.: **29/771,591**(22) Filed: **Feb. 24, 2021****Related U.S. Application Data**

(62) Division of application No. 29/664,266, filed on Sep. 24, 2018, now Pat. No. Des. 914,696.

(30) **Foreign Application Priority Data**

Mar. 23, 2018 (DE) 40 2018 100 313.1

(51) LOC (13) Cl. **14-04**

(52) U.S. Cl.

USPC ..... **D14/485**(58) **Field of Classification Search**

USPC D14/485-495

CPC G06F 3/048; G06F 3/0481; G01C 21/36;

B60K 37/00

Primary Examiner — Daniel J Domino

(74) Attorney, Agent, or Firm — Lucas & Mercanti, LLP;
Klaus P. Stoffel(57) **CLAIM**

The ornamental design for the display screen or portion thereof with graphical user interface, as shown and described.

DESCRIPTION

The FIGURE is a front view of a display screen or portion thereof with graphical user interface showing my new design.

The broken lines showing a display screen illustrate portions of the article and form no part of the claimed design.

1 Claim, 1 Drawing Sheet---
